UNITED STATES PATENT OFFICE.

UZZIEL P. SMITH, OF AKRON, OHIO.

VEHICLE-WHEEL.

No. 893,270.

Specification of Letters Patent.

Patented July 14, 1908.

Application filed September 19, 1906. Serial No. 335,177.

To all whom it may concern:

Be it known that I, UZZIEL P. SMITH, a citizen of the United States, residing at Akron, in the county of Summit and State of Ohio, have invented a certain new and useful Improvement in Vehicle-Wheels, of which the following is a full, clear, and exact description.

The object of the present invention is to provide a vehicle wheel which shall have a cushion of any suitable form or type interposed between the hub and the rim or spoke section.

The general type of wheel is one well known in the art, being designed to hold the cushion, which may be composed either of springs or a pneumatic tube, near the center of the wheel in order that it may be free from the wear and tear to which it is subject when placed outside of the rim. One of the great difficulties found in connection with such wheels is the provision of a rotary driving connection between the hub and the spoke section which shall permit of a relative oscillation between the two in all directions in the vertical plane of the wheel and be such as not to permit a transmission of torsional strain to the cushion. The structure which I have devised is designed to overcome the difficulties above set forth, and to attain all of the advantages which should accompany this particular type of wheel.

Referring to the accompanying drawings, which form a part of this application, Figure 1 is a transverse vertical section of an embodiment of my invention in which a cushion consists of spiral springs. Fig. 2 is a section taken at right angles to Fig. 1 along the line 2—2. Fig. 3 is a section at right angles to Fig. 1 taken along the line 3—3, broken away in part to show the location of one of the driving disks.

The hub section A of the wheel is mounted upon and secured to the driving shaft A' in any suitable manner and has seats A² thereabout for the cushioning devices, which, in the present instance, are as above noted, composed of spiral compression springs B. It is obvious that these springs might be replaced by pneumatic balls or a tube or equivalent devices.

Projecting from the hub in a radial plane is a web A³ having pockets A⁴ therein in which are snugly fitted disks C capable of rotative movement in the pockets. These pockets are distributed around the web in

such manner as to allow for a proper distribution of the supporting and driving strains, and it will be noted that in the present instance I have provided three of these pockets 60 equidistant from each other. The web referred to may be located intermediate of two sets of cushioning devices, which arrangement has some apparent advantages, but this arrangement is not essential, since the 65 cushioning devices may be all located on one side of the web, if for reasons of construction this is deemed preferable.

The rim or spoke section D has a ring D' surrounding the hub adapted to inclose the 70 cushioning devices, the central opening of the ring being of sufficient diameter to permit such play as the cushioning devices are designed to take care of.

Projecting internally from and rigid with 75 the spoke ring is a web D⁴ designed to lie adjacent to the web projecting from the hub. In this second web also I have provided pockets D² for receiving disks C', which pockets are located so as to mate with the 80 pockets A⁴ in the web projecting from the hub. Each pair of mated disks is provided with an eccentric connection in the form of a stub or pin C². Owing to the fact that the connection between the several pairs of disks 85 C' is eccentric and each disk is free to rotate about its own axis, it is obvious that relative movement between the hub and the spoke ring may take place in all directions in the vertical plane of the wheel. For the 90 purpose of permitting this relative movement, it is of course necessary that there be a space outside of the perimeter of the web projecting from the hub sufficient to allow of the relative movement of the parts, and in 95 the event that this web is located in the approximately central position in which it is shown in Fig. 1, it will of course be necessary to provide the space for the proper play by making an annular recess D³ in the spoke 100 ring D'.

For the purpose of holding the spoke ring against relative sidewise end movement along the shaft, I provide the hub with guiding and retaining rings or plates A⁵ which 105 may be secured in any way desired.

From the structure above described, it is plain that the relative vibration between the hub and the spoke ring in the plane of the wheel is not interfered with by the driving 110 disks, being controlled as to its extent by the cushioning devices interposed between the

two sections. The rotative movement of the hub section is transmitted to the spoke section by means of the mated pairs of disks which are each free to rotate in their respective pockets and are therefore capable of transmitting motion without in any manner affecting the vibratory motion in the radial direction. In this respect they constitute a connection different from any heretofore known, which is positive in its character, being devoid of looseness of play or any other feature which might produce shock or cause the rotative motion to be transmitted through the cushioning device.

Having thus described my invention, I claim:

1. A wheel comprising a hub section and a rim section, a cushion between said sections adapted to receive the shock of relative movement between the two, a driving connection between said hub section and rim section comprising a disk revolvably mounted on a hub section and eccentrically connected with a disk revolvably mounted on the rim section.
2. A wheel comprising a hub section and a rim section, a cushion between said sections adapted to receive the shock of relative

movement between the two, a driving connection between said hub section and rim section comprising a revoluble disk carried by the hub section and eccentrically connected with a revoluble disk carried by the rim section, said disks being so mounted that the individual axis of rotation of each disk remains fixed relatively to the section by which the disk is carried.

3. A wheel comprising a hub section and a rim section, cushioning means between said sections, each section provided with pockets and disks revolvably fitted in said pockets, said pockets and disks being so located that when the wheel is assembled, the disks in the one section may be brought face to face with the disks in the other section, the disks of one section being each pivotally connected with a disk of the other section at a point eccentric to each disk.

In testimony whereof, I hereunto affix my signature in the presence of two witnesses.

UZZIEL P. SMITH.
